UNITED STATES PATENT OFFICE.

CHARLES A. WOOD, OF CLAY CENTER, KANSAS.

MOLD.

Application filed July 6, 1926. Serial No. 120,695.

My invention relates to new and useful improvements in molds, and one object is to provide a mold which can be readily closed and opened preparatory to forming a casting and discharging the latter.

Another object is to provide a mold with mechanism for facilitating discharge of the finished castings.

Other objects will hereinafter appear, and in order that the invention may be fully understood reference will now be had to the accompanying drawings, in which:

Fig. 1 is a plan view of the mold with the sections thereof in closed position and the handles partially broken away.

Fig. 2 is an end elevation of the mold with the handles partially broken away.

Fig. 3 is an irregular cross section on line 3—3 of Fig. 1.

Fig. 4 is a slightly enlarged horizontal section on line 4—4 of Fig. 2 and with the mold in inverted position.

Fig. 5 is an inverted end elevation of the mold in open position.

Fig. 6 is an enlarged cross section of a plunger and a core pin employed in carrying out the invention.

In carrying out the invention I employ mold sections 2 and 4 having registering mold sections 2 and 4 having registering 30 chambers 6 and 8, in which the castings are formed. The sections 2 and 4 are provided at their upper portions with registering gates 10 and 12, which communicate with the chambers 6 and 8, respectively.

Guide means in the form of rods 14 and sleeves 16 are provided for operably connecting the sections 2 and 4 and guiding the latter as they are opened and closed. The rods 14 are slidably mounted in the sleeves 16 and 40 secured to the ends of the section 2, while the sleeves 16 are secured to the ends of the section 4. The rods 14 are provided at their free ends with suitable heads 18 for actuating a cross head 20 slidably mounted upon 45 said rods 14.

22 designates a pair of brackets secured to the longitudinal outer side of the section 2 and provided with horizontal slots 24 in which a fulcrum 26 is slidably mounted. Said 50 fulcrum 26 is provided with a pair of core pins 28 projecting through the section 2 and reinforced with bushings 30 which prevent the molten metal from flowing into the openings through which said core pins 28 project.

55 32 designates a lever rockably mounted upon the fulcrum 26 and equipped with a

rigidly mounted handle 34. The free end of the lever 32 is pivotally connected at one end of a pair of links 36 which are pivotally connected at their opposite end to a lug 38 secured to the bottom of the section 4. The lever 32 is yieldably held from rocking upon its fulcrum 26 by means of a coil spring 40 secured at one end to said lever 32 and at its opposite end to the reduced end of a plate 42 secured to the longitudinal outer side of the mold 2.

The section 4 is provided with a fixedly mounted handle 44 extending freely through an opening 46 in the cross head 20. The handle 44 is provided with a transverse pin 48 to which a pair of core pins 50 are secured. The core pins 50 project through the section 4 and are provided near their inner ends with semicircular bushings 52 which slidably engage the semicircular portions 54 of a pair of tubular plungers 56 through which said core pins 50 extend. The bushings 52 and the semicircular portions 54 of the plungers 56 prevent the molten metal from flowing into the openings through which said plungers 56 extend into the section 4. The plungers 56 are held against the cross head 20 by coil springs 58 which are interposed between the adjacent side of the section 4 and heads 60 at the outer ends of said plungers 56.

62 designates a plunger extending into the lower portion of the section 4 and provided at its outer end with a head 64 which is held against the cross head 20 by a coil 90 spring 66 interposed between said head 64 and the adjacent side of the section 4. Normally the cross head 20 is held by the outward pressure of the plungers 56 and 62 against a stop 68 secured between the section 4 and the lug 38.

In practice the metal or other material to form the casting is poured into the mold while the sections 2 and 4 are in closed position. The mold is then inverted and opened 100 by raising the handle 34 to the position shown by Fig. 5. Raising of the handle 34 rocks the lever 32, causing it to push upon the links 36 and thereby force the sections 2 and 4 apart against the action of the springs 40, 58 and 66. The resistance offered to the rocking movement of the lever 32 causes the latter to push the fulcrum 26 against the outer ends of the slots 24. As the fulcrum 26 moves outwardly as stated it withdraws the core pins 28 from the chambered portion of the section 2. Opening of the mold also causes 105 110

the heads 18 of the rods 14 to engage and draw the cross head 20 towards the section 4, thereby forcing the plungers 56 and 62 inwardly against the action of the springs 58 and 66, respectively, so that they will deliver the casting from the section 4. After the casting has been delivered pressure on the handles 34 and 44 is relieved sufficiently to permit the springs 40, 58 and 66 to close the mold. The springs 58 and 66 also force the respective plungers 56 and 62 outwardly and they in turn force the cross head 20 outwardly until checked by the stop 68.

From the foregoing description it is apparent that I have provided a mold of large capacity due to the rapid manner in which it may be opened and closed, and while I have shown and described the preferred construction, combination and arrangement of parts I reserve all rights to such changes and modifications as properly fall within the spirit and scope of the invention as claimed.

Having thus described my invention, what I claim and desire to secure by Letters Patent, is:

1. In an invertible mold of the character

described, two chambered sections, sleeves fixed to one section, rods fixed to the companion section and slidably mounted in said sleeves, a cross head slidably mounted upon the rods, plungers operably mounted in one section, means on the rods for causing said cross head to force the plungers inwardly when the sections are opened, and spring means for forcing the plungers outwardly when the sections are closed.

2. In a mold of the character described, mold sections, means operably connecting said sections for holding the latter in proper relation to each other when opened or closed, a fulcrum slidably associated with one section, a core pin secured to said fulcrum and extending into the associate section, a lever mounted upon said fulcrum for causing the latter to move said core pin outwardly and inwardly when the sections are opened and closed, a link connecting said lever and the companion section, and means for actuating said lever to effect the opening and closing of the sections.

In testimony whereof I affix my signature.
CHARLES A. WOOD.
